Patented Jan. 11, 1916.

JOHN NELSON Inventor

By *Watson E. Coleman*

Attorney

UNITED STATES PATENT OFFICE.

JOHN NELSON, OF STAMFORD, NEBRASKA.

CLOTHES-LINE.

1,168,102.

Specification of Letters Patent. Patented Jan. 11, 1916.

Application filed November 1, 1915. Serial No. 59,092.

To all whom it may concern:

Be it known that I, JOHN NELSON, a citizen of the United States, residing at Stamford, in the county of Harlan and State of Nebraska, have invented certain new and useful Improvements in Clothes-Lines, of which the following is a specification, reference being had to the accompanying drawings.

10 This invention relates to an improved clothes line and has for its primary object to provide a line for hanging or suspending clothes, which is so constructed that the use of pins or other analogous fastening elements is rendered unnecessary.

15 It is a more particular object of the invention to provide a clothes line embodying a plurality of links each constructed from a single length of resilient metal wire bent upon itself to provide end loops in the link, the end portions of the wire being extended along and in contact with the medial portion thereof and the extremities of the wire permanently soldered together, said end 20 portions being provided with spaced bends therein to increase the gripping action of the same upon the articles of clothing interposed between said ends of the wire and its medial portion.

25 The invention has for a further general object to improve and simplify the construction of devices of the above character, increase their durability and efficiency in practical operation, and reduce the manufacturing cost thereof to a minimum.

30 With the above and other objects in view, my invention consists in the novel features of construction, combination and arrangement of parts to be hereinafter more fully 35 described, claimed and illustrated in the accompanying drawing, in which,

Figure 1 is a plan view of a portion of a clothes line constructed in accordance with the preferred embodiment of my invention; 40 Fig. 2 is an enlarged fragmentary elevation showing a fabric article held in the line; Fig. 3 is a section taken on the line 3—3 of Fig. 2; and Fig. 4 is a section taken on the line 4—4 of Fig. 2.

45 Referring in detail to the drawing, 5 indicates one of the links of the clothes line. Each link is constructed from a single length of resilient metal wire which is bent upon itself at spaced points to provide the 55 terminal loops 6 in the link. The end portions 7 of the wire extend along the medial

portion thereof and are normally in contact with the same, as clearly shown in Fig. 1. The extremities of the wire are permanently soldered or otherwise fixed together, as indicated at 8. Each end portion 7 of the wire link has a plurality of spaced bends or longitudinally curved sections 9 therein which constitute gripping jaws.

60 The several links of the clothes line are connected together in the manner shown in Fig. 1, the terminal loop 6 of each link being engaged in one of the terminal loops of an adjacent link so that the links remain 65 permanently connected together. It will be understood that the clothes line may be constructed in any desired length and the individual links thereof are free to assume various positions relative to each other within certain limits. In applying the articles of 70 fabric to the line, the same are engaged within the wide terminal loops 6 of the links and the articles forced inwardly between the medial portion of the link wire and the ends 7 thereof so that said sections will be 75 sprung outwardly and the fabric material will thus be received in and gripped by the curved jaw sections 9 of the wire, as clearly shown in Fig. 2 of the drawing. Thus, the 80 articles will be securely clamped and held in 85 the several links in such manner as to preclude the possibility of their release even though the articles are violently agitated by strong winds. It will be understood that 90 the articles can be very easily and quickly 95 disengaged from the links of the line by simply grasping the side of the end loops 6 from which the ends 7 of the wire are extended, and pulling outwardly upon the same, thereby loosening the gripping action 95 of the jaws 9 upon the articles so that said articles can be withdrawn from between the jaws and the opposed medial portion of the wire link.

100 From the foregoing description, taken in connection with the accompanying drawing, it is believed that the construction, manner of use and several advantages of the invention will be clearly and fully understood. By means of my improved wire 105 link construction for the clothes line, the necessity of using pins or other fastening elements for securing the articles to the line, is obviated. As each link is formed from a single length of wire which may be readily 110 bent to produce the several structural features of the link, it is apparent that the in-

vention may be produced at comparatively small manufacturing cost. The device is also very durable, as well as reliable and efficient in practical use.

While I have shown and described the preferred construction and arrangement of the several features of the device, it is to be understood that the same is susceptible of considerable modification therein and I, therefore, reserve the privilege of adopting all such legitimate modifications as may be fairly embodied within the spirit and scope of the invention as claimed.

Having thus fully described my invention, what I desire to claim and secure by Letters Patent is:—

A clothes line consisting of a series of

links each formed from a single length of wire bent upon itself to produce terminal loops for connection to the corresponding loops of adjacent links, the end portions of the wire being extended along the medial portion thereof and resiliently engaged with the same, said end portions of the wire being permanently connected together at their extremities and each end portion having a plurality of gripping jaws formed therein.

In testimony whereof I hereunto affix my signature in the presence of two witnesses.

JOHN NELSON.

Witnesses:

L. B. CARRAHER,
F. L. ARFORD.
